UNITED STATES PATENT OFFICE.

JOHN A. RENNIE, OF LYNDHURST, NEW JERSEY, ASSIGNEE TO UNDERWOOD TYPE-WRITER COMPANY, OF NEW YORK, N. Y., A CORPORATION OF DELAWARE.

TYPE-WRITING MACHINE.

1,098,840.

Specification of Letters Patent.

Patented June 2, 1914.

Application filed October 27, 1910. Serial No. 589,456.

To all whom it may concern:

Be it known that I, JOHN A. RENNIE, a citizen of the United States, residing in Lyndhurst, in the county of Bergen and State of New Jersey, have invented certain new and useful Improvements in Type-Writing Machines, of which the following is a specification.

This invention relates to rolls such as used for feeding the paper in typewriting machines, and particularly to those which run upon a rotatable platen around which the work sheet is wrapped or carried.

The soft - rubber paper - feeding rolls usually employed upon typewriting machines consist of solid cylinders, which are capable of only such slight yielding as is due to the consistency of the rubber. Such rolls are not found to carry the paper accurately around the rotating platen. Moreover it is usually difficult to introduce a sheet or sheets between the feed roll and the platen, unless the feed roll is cast off. One difficulty is that the leading end of the sheet tends to separate the feed roll from the platen, and hence the roll can only be driven through the medium of the paper itself, and this operation often proves unsuccessful. Moreover, the pressure roll is usually sprung pressed with so much force against the platen, that often both the platen and the roll may be rotated for an indefinite period without picking up the work sheet which is being presented to the bite of the roll and platen.

The principal object of this invention is to provide a roll which will overcome these difficulties, and which will be positive and reliable in action, inexpensive to manufacture, and not liable to deteriorate.

In the accompanying drawings, Figure 1 is a perspective bottom view of the platen, a portion of the platen frame, and the pressure rolls running upon the platen, of the well-known Underwood front strike typewriting machine; the rear or main rolls being constructed according to the preferred form of the present invention. Fig. 2 is a sectional perspective view taken crosswise through the body of one of the main rolls. Fig. 3 is a sectional side elevation to illustrate the normal relation of the platen and one of the main pressure rolls, and also to

show how the rolls and platen readily pick up a sheet of paper which is presented thereto. Fig. 4 is a view similar to Fig. 3, but showing a number of sheets being fed by the rolls and platen. Fig. 5 is a longitudinal section of the form of roll seen at Figs. 1 and 2. At this figure, the roll is of a pneumatic construction, that is, it contains a gas (which may be wholly or partly air) under compression. Fig. 6 is a roll similar to that seen at Figs. 1 to 5, but not containing a body of compressed air or gas as is the case at Fig. 5. Fig. 7 is a sectional diagram illustrating one method of making the roll (minus the metal core) seen at Fig. 5.

The cylindrical platen 1 of the Underwood or other typewriting machine, which is usually rotatable by a knob 2, or otherwise, is provided with a paper guide in the form of a rear inclined shelf or plate 3, which curves forwardly under the platen 4. Upon a horizontal rod 5, which extends along under the platen from end to end of the platen frame, are pairs of arms 6, 7, and 8, 9, carrying forward pressure rolls 10 and rear pressure rolls 11, said rolls mounted on forward and rear shafts 12 and 13 journaled in said arms. The shafts and arms are pressed toward the platen by springs 14.

The preferred form of my improved pressure roll is illustrated as mounted on the rear shaft 13 and similar rolls may be mounted on the front shaft 12 if desired; and of course these rolls may be used in still other connections.

In the preferred form of my invention, the roll comprises a tubular metal core 15, mounted loosely upon the shaft 13, and having at its ends heads 16, between which the soft rubber body of the roll is confined. The roll itself comprises a cylindrical rubber core piece 17 and a peripheral portion 18 to run upon the platen; said portions being separated so that the roll is hollow, but their ends being joined at 19; the core portions 17, the peripheral portions 18 and the ends 19 being preferably integral. The ends 19 may be formed with cup portions 20 to receive the heads 16. The core portions 17 may be vulcanized to the metal cores 15, if desired, and one or both of the heads 16

may, if desired, be applied to the core after the vulcanization.

One method of manufacturing the rubber roll without the metal core 15 is illustrated at Fig. 7, in which a four-part mold is shown, comprising two similar opposite or complementary outer cupped portions 21, 22, joining at their edges along the line 23, and two central or axial core pieces 24, 25, abutting within the mold. The unvulcanized rubber may be made in suitable parts and inserted in the mold, and form therein a hollow cylinder, as shown at 18^a, Fig. 7. Vulcanization joins the parts together into one piece. Within the hollow 26 of the roll is inserted a small quantity of a suitable gas-forming agent, as 27, which, during the heat of vulcanization, will expand and form a permanent gas. This gas-forming agent may be ammonium carbonate, which is usually employed in making hollow rubber balls. Sufficient of this gas-producing agent may be used to permanently expand the roll from the cylindrical shape at Fig. 7 to the barrel shape seen at Fig. 5; the gas being sealed in the roll and in a state of slight but permanent compression, producing a bilge on the periphery of the roll. It will be understood, however, that by using a smaller quantity of gas-producing agent 27, the rubber may be vulcanized in the cylindrical shape shown at Fig. 7, and retain such shape after vulcanization. In such a case, the roll may afterward, if desired, be expanded to the Fig. 5 shape by any suitable means. At Fig. 3 the front rolls 10 are shown as having the hollow cylindrical form indicated at Fig. 7. The rubber of the roll may be of such softness that when springs 14 of suitable force are employed, the main rear roll in cross section will assume the form seen at Fig. 3, the side thereof in contact with the platen being flattened along the middle portion of the barrel; such portion of course being not firmly supported by the ends 19 of the roll, and hence being of a very yielding quality. As a consequence, the roll contacts with the surface of the platen for a considerable distance around the periphery of the latter, instead of substantially at a single point, as is the case with the solid rolls commonly employed, as at 10^a, Fig. 4. This feature of the roll is of considerable importance, as it causes the paper to hug closely to the platen, and conduces materially to the accurate feed of the paper relatively to the platen.

When introducing a single sheet of paper 28, the leading edge thereof, as will be seen at Fig. 3, is caught between the roll 11 and the platen, so as to be driven by the roll as well as by the platen, while a substantial portion of said roll is still in contact with the platen itself, so that the roll is directly driven by the platen while said roll is itself

driving the sheet. In other words, the sheet does not separate the roll bodily from the platen when it is attempted to introduce the sheet, as is often the case in typewriters of present day construction, but is gripped between two drivers, both of which are in positive action. For this reason the sheet is very easily introduced into the machine, and is instantly picked up by the roll and platen and properly fed forward to the printing point, and the feed of the sheet is kept true until it leaves the rolls. It will be seen that a considerable area both longitudinally and circumferentially of each roll 11 is constantly running upon the platen or upon the paper, thus making a very efficient paper feed.

The yielding of the swollen portion 18 of the roll is due partly to its being supported by its ends instead of being supported throughout its length, as heretofore. The invention, however, includes hollow rolls, whether or not they contain gas in a state of compression, or even if they are cylindrical in form, as at Figs. 4 and 7, since these rolls would yield much more readily than the ordinary solid rubber rolls, with the effect seen at Figs. 3 and 4, and with the same beneficial results.

At Fig. 4 it will be seen that if a large number of sheets is inserted, the roll may yield still more than at Fig. 3, if a strong spring 14 is employed; or in some cases the arm 8 which supports the roll may be made unyielding, the range of yield of the bilge portion 18 of the roll being sufficient to accommodate one sheet, as at Fig. 3, or many sheets, as at Fig. 4. While I prefer the barrel shape illustrated, it will be understood that the form of the hollow roll may be modified within the scope of the invention.

In the form of the invention shown at Fig. 6, the roll consists of a single hollow bilged body 18^b, having ends 19^a, to fit upon the core 15; the core piece 17 being omitted, and the roll merely containing air at ordinary pressure. Since there is lack of interior compressed gas support, the wall 18^b may be made thicker than the wall 18 at Fig. 3, so as to give the requisite firmness.

Other variations may be resorted to within the scope of the invention.

Having thus described my invention, I claim:

1. The combination with a revoluble platen, of a feed roll to run thereon comprising a bilged yielding body, a core portion, and ends, said body, core portion and ends being integral, and means for revolubly supporting said roll.

2. A feed roll to run on a revoluble platen, said feed roll comprising a bilged body, a core portion, and ends, said body, core portion and ends being integral, said body containing gas under pressure.

3. A feed roll to run on a revoluble platen, said feed roll comprising a core having heads, and a soft rubber bilged body confined between said heads.
- 5 4. A feed roll to run on a revoluble platen, said feed roll comprising a core having heads, and a soft rubber bilged body having integral supporting ends confined between said heads, said roll having an integral core-piece to fit upon said core.
- 10 5. The combination with a revoluble platen, of a feed roll to run thereon, comprising a core having heads, and a soft rubber bilged body of continuous structure confined between said heads and having an integral core-piece to fit upon said core and vulcanized thereto.
- 15 6. The combination with a revoluble platen, of a feed roll to run thereon, comprising a core having heads, and a soft rubber bilged body confined between said heads and having an integral core-piece to fit upon said core and vulcanized thereto, and containing a body of gas under pressure.
- 20 7. The combination with a revoluble platen, of a bilged soft rubber feed roll of continuous structure to run thereon, the middle portion of said roll being more yielding than its end portions.
- 25 8. The combination with a rotatable platen, of a feed roll to run thereon, said roll having a hollow soft rubber body with yielding ends, and means supporting said roll at said ends to communicate pressure whereby said roll is flattened against the platen.
- 30 9. The combination with a rotatable platen, of a feed roll to run thereon comprising a hollow bilged soft rubber body having yielding ends, and means to flatten said body against the platen.
- 35 10. The combination with a rotatable platen, of a feed roll to run thereon comprising a hollow bilged soft rubber body with yielding ends, and means to flatten said body against the platen, said body and ends being integral.
- 40 11. The combination with a platen, of forward and rear pressure rolls to run thereon, each of said rolls having a hollow soft rubber body of continuous structure, capable of spreading against the platen, and means to spread the rolls against the platen.
- 45 12. The combination with a rotatable platen, of a feed roll to run thereon, said roll comprising a hollow soft rubber body of continuous structure, capable of spreading against the platen, and means for spreading said body against the platen.
- 50 13. The combination of a feed roll to run on a rotatable platen, said roll comprising a hollow bilged soft rubber body of continuous structure, and means to flatten the same against the platen.
- 55 14. The combination of a feed roll to run
- on a rotatable platen, said roll comprising a hollow bilged soft rubber body having ends, and means applying pressure at said ends to flatten the roll against the platen.
- 60 15. The combination of a feed roll to run on a rotatable platen, said roll comprising a bilged soft rubber body having ends whereby it is supported, and means to transmit pressure through said ends to the bilged body to flatten the roll against the platen.
- 65 16. The combination with a revoluble platen, of a feed roll to run thereon, said roll comprising a body of continuous structure expanded by an interior body of gas to create a centering peripheral enlargement of said body, and means for flattening said expanded body against the platen.
- 70 17. A feed roll to run on a revoluble platen, said feed roll comprising a bilged body of continuous structure expanded by an interior body of gas.
- 75 18. A feed roll to run on a revoluble platen, said feed roll comprising a bilged yielding body, a core portion, and ends, said body, core portion and ends being integral.
- 80 19. A feed roll to run on a rotatable platen, said roll having a hollow soft rubber bilged body of continuous structure with yielding ends.
- 85 20. A feed roll to run on a rotatable platen, said roll having a hollow soft rubber bilged body of continuous structure with soft rubber ends.
- 90 21. The combination of a bearing rod, and a plurality of spaced feed rolls mounted on said rod to bear against a rotary platen, each roll comprising a hollow barrel-shaped soft rubber body of continuous structure.
- 95 22. The combination of a bearing rod, and a plurality of spaced feed rolls mounted on said rod to bear against a rotary platen, each roll comprising a hollow barrel-shaped soft rubber body of continuous structure containing a gas under compression.
- 100 23. In a typewriting machine, the combination with a rotary platen, of an elastic feed roll whose periphery is increasingly distended and increasingly yielding toward the center as compared with the ends, said center sufficiently soft and yielding under feeding pressure to lap a substantial distance around the platen, to thereby afford ample contact with said platen to be driven thereby at one place, while simultaneously presenting at another place an introductory lip to receive and draw inwardly the leading edge of the work-sheet supplied to the platen.
- 105 24. In a typewriting machine, the combination with a rotary platen, of a hollow feed roll of soft rubber located at the introductory side of the platen, and means for pressing the roll against the platen, the periphery of said roll being increasingly distended toward the center and sufficiently yielding
- 110 115 120 125 130

at the center to spread or lap around the platen for a substantial distance under feed pressure, to thereby afford ample feed contact with said platen to be rotated thereby,
5 while simultaneously presenting an introductory lip to receive and draw inwardly the leading edge of the work-sheet supplied to the platen; the roll having solid ends of soft

rubber not so yielding as its middle, to be effective in pressing the work-sheet firmly 10 against the platen.

JOHN A. RENNIE.
